LEO A. SCHAUER AND ERNEST C. MYERS, OF PITTSBURGH, PENNSYLVANIA.

SURFACING MACHINE FOR COMMUTATORS.

1,416,981.

Specification of Letters Patent. Patented May 23, 1922.

Application filed June 7, 1920. Serial No. 387,131.

To all whom it may concern:

Be it known that we, LEO A. SCHAUER and ERNEST C. MYERS, citizens of the United States of America, residing at Pittsburgh, 5 in the county of Allegheny and State of Pennsylvania, have invented certain new and useful Improvements in Surfacing Machines for Commutators, of which the following is a specification.

10 The present invention relates to surfacing machines for commutators as commonly used on automobile engines, and the present surfacing and "truing" device is particularly designed to be of service in connection with 15 commutators of the type used on "Ford" automobile engines. The device in hand possesses the following advantages which will be brought out more fully as the description proceeds. The surfacing machine 20 which we have devised is very simple in construction, and in the number of parts, many of the elaborate minor parts commonly found in devices of this kind, being purposely eliminated, and yet the work performed on the commutators in the way of 25 facing the internal annular band of the latter is just as perfect as the more elaborately designed surfacing machine.

A means of holding the commutator on 30 the device while being surfaced is provided, and also a means is provided for increasing or decreasing the pressure exerted by the cutting tool, according to the desired compression against the face of the commutator ring, as will be further explained hereinafter. Other features will also be described below.

In the drawings forming part of this 35 specification, we have illustrated one complete example of our invention, in which:

Figure 1 is an end view of the device taken from the left of Figure 2.

Figure 2 is a side view of the invention, 40 partly in section, with a commutator or distributor shown in operative position thereon.

Figure 3 is a vertical section on line 3—3 of Figure 2.

Figure 4 is a side view of a portion of the device shown in Figure 2.

50 Figure 5 is a bottom plan view of the under side of the cutting tool used in our invention.

Figure 6 is a side view of the cutting tool used, and a partial section of associated 55 parts.

Figure 7 is a front view of the cutting tool shown in Figure 6.

Figure 8 is a perspective view of a modified form of cutting tool.

The numeral 1 indicates a metal holder or 60 chuck having an integral supporting member 2, provided with jaws 3, 4 for attaching the device to a bench 5, by means of the screw 6 as shown in Figure 2. The enlarged end 7 of the chuck 1 is cut away at 8, 8, and 65 a revoluble member 28 passes through the holder stem 27 as shown in Figure 2. The end 9 of the member 28 is screw-threaded preferably at 10, so that the collar-like member 11, can be rigidly mounted thereon. The 70 member 11 has a projection 12 provided with a radially disposed chamber 39, a cutting tool 13 slidably mounted therein. A slotted aperture, 14, and a pin 15 form a means of 75 securing the tool 13 against removal from the member 11. The cutting tool 13 is of shape shown in Figures 5, 6 and 7 and the bottom thereof being made as shown in Figure 5, indented or cut into sharpened cutting 80 edges like those of a file, for cutting the face 16 of the annular commutator ring 17, but it is understood that any other form of cutting edge can be used on the cutting tool 13, if desired, such as the edge shown in Figure 8, or the like. A spring can be inserted in 85 the slot at 18 to hold the tool 13 in a retracted position if desired, but this is found not essential in practice, as the tool can be placed at its highest position as seen from an inspection of Figure 2, in which case it is 90 seen that the tool 13 will at once take a retracted position due to gravity, and so the commutator 19, and ring 17 can at once be placed in position on the chuck, without any interference from the cutting tool 13, as is 95 readily understood. The chuck 1 has a number of indentations 20, 20 adapted to receive the wire connection projections 21, 21, etc., thereby preventing the commutator from turning on the chuck 1 when the tool 13 is 100 revolved. A revoluble band 22 pivoted on the chuck at 23, and having a screw 24 adapted to engage in the end of the commutator at 25 is used or holding the commutator 19 on the holder 1, and against the 105 shoulder 26 formed on the holder 1. When desired the band holder 22 can be thrown up to position at 29, in order to remove the commutator 19 from the chuck as is readily appreciated.

On the end 30 of the revoluble member 28 is mounted the handle 31, by means of the screw-thread 38, or in any other suitable manner, so that the handle and spindle 28 are rigidly held together, and when the handle 31 is revolved that with it the member 28, and collar 11 move as a unit to operate the tool 13. Within the revoluble spindle 28 is rotatably mounted the adjusting screw 32, which is operated along the pipe 28 by means of the screw threads 33, and thumb prongs 34. The outer end 35 of adjusting screw 32 is beveled, so that as the screw 32 is advanced outwardly to the left as seen in Figure 2, that the cutting tool 13 is pushed outwardly and in more insistent contact with the ring 17 of the commutator 19. This enables the operator to use any amount of pressure on the ring when truing and facing same desired, and when the commutator is to be removed after surfacing, by retracting screw 32 to the right the tool 13 at once becomes loose, and enables the commutator to be removed from the chuck 1. The screw 32 may be locked in adjusted position by the small screw 36 if desired, the latter being mounted in the portion 37 of the handle 31. From which it is seen that I have provided a device of very few parts, and of exceedingly simple construction, which readily accomplishes the work of refacing the inner rings of commutators for automobile engines.

We claim:—

- 35 1. In a surfacing machine for commutators, a chuck, a revoluble spindle mounted therein, a cutting tool on the end of the spindle, and means for adjusting the intensity of pressure exerted by the cutting tool when the revoluble spindle is operated.
2. In a surfacing machine for commutators, a chuck, a revoluble spindle mounted therein, a cutting tool on the end of the spindle, an adjusting screw mounted within said spindle, and a cone-shaped end on the adjusting screw adapted to adjust the intensity of pressure exerted by said tool when the aforesaid spindle is operated.
3. In a surfacing machine for commutators, a chuck, a revoluble spindle mounted therein, a collar on the end of said spindle, a radially disposed chamber formed in the collar and spindle, a cutting tool having a slotted shank adapted to reciprocate within said chamber, a securing pin passing through the collar and shank slot, an adjusting screw having a cone-shaped end adapted to engage against the end of the cutting tool shank, and means for locking the revoluble spindle and adjusting screw together when the said spindle is operated.
4. In a surfacing machine for commutators, a chuck, a revoluble spindle axially

mounted therein, a retractable cutting tool on the end of the spindle, an adjusting screw 65 co-axially mounted within the revoluble spindle, and having a cone-shaped end adapted to adjustably engage against the inner end of the cutting tool, means for holding the cutting tool in a retracted position 70 when a commutator is being placed in position on the chuck, a pivotally mounted revoluble band on the chuck having a thumb-screw passing therethrough to hold the said commutator in position in a longitudinal 75 direction when the aforesaid revoluble spindle is operated.

5. In a surfacing machine for commutators, a chuck having an enlarged end, an annular recess formed in said end adapted 80 to receive the end of a commutator, a semi-circular band pivotally mounted on the chuck, having a thumb-screw passing therethrough to form a longitudinal securing means for said commutator, means for preventing revolution of the commutator on the chuck, a revoluble spindle carried in chuck, a retractable cutting tool on the spindle, an adjusting screw within the spindle engaging against the end of the cutting tool, and 90 means for locking the spindle and adjusting screw together when the revoluble spindle is operated.

6. In a commutator grinder, a chuck, a revoluble spindle mounted therein, a collar 95 having a radially disposed projection thereon, carried on the end of the spindle, a radially disposed chamber in said projection, a cutting tool having a slotted shank reciprocating within said chamber, an arc-shaped 100 cutting edge on the cutting tool, a pin mounted in the collar projection and passing through the shank slot for preventing disengagement of the cutting tool, adjustable means for controlling the intensity of pressure exerted by the cutting tool, and means for operating the revoluble spindle before described.

7. In a commutator grinder, a collar having a radially disposed projection thereon, 110 a radial chamber in said projection, a cutting tool having a slotted shank, reciprocating within said chamber, an arc-shaped cutting edge on the cutting tool, a pin mounted in the collar projection and passing through 115 the shank slot for preventing disengagement of the cutting tool from the aforesaid collar chamber.

In testimony whereof we affix our signatures.
